(57) **CLAIM**

The ornamental design for a multiple shower head system, as shown and described.

DESCRIPTION

FIG. 1 is a front elevation view of a shower assembly, showing our new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a top, front and right side perspective view thereof; and,

FIG. 8 is a perspective view showing our new design in a shower environment.

The broken lines shown represent portion of a shower head and form no part of the claimed design.

1 Claim, 5 Drawing Sheets
